HYDRAULIC VANE MOTOR

Herman Horlacher, Cincinnati, Ohio, assignor to
 The Cincinnati Milling Machine Co., Cincinnati,
 Ohio, a corporation of Ohio

Application July 6, 1937, Serial No. 152,200

6 Claims. (Cl. 121—99)

This invention relates to hydraulic motors and more particularly to improvements in vane type motors.

One of the objects of this invention is to provide a motor of the above type which is especially suitable for heavy work.

Another object of this invention is to provide improved automatic means for controlling the rate of movement of a fixed stroke motor in a manner to eliminate sudden stops at the end of the stroke which might otherwise cause damage to the parts.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

Referring to the drawings in which like reference numerals indicate like or similar parts:

Figure 1 is a section through a motor embodying the principles of this invention.

Figure 2 is an expanded view of the rate control cam.

Figure 3 is an end view of the motor shown in Figure 1 as viewed from the left end of that figure.

Figure 4 is a section on the line 4—4 of Figure 1.

Figure 5 is a detail section on the line 5—5 of Figure 3.

Figure 6 is a detail section on the line 6—6 of Figure 3.

Referring to Figure 1, the reference numeral 10 indicates the main housing or casing of the motor in which is formed a cylindrical chamber 11. A drive shaft 12 passes through the center of this chamber and is journaled at 13 and 14 in the opposing walls 15 and 16 respectively of the housing. The center portion 17 of this shaft has integral splines 18, as more particularly shown in Figure 4, upon which is mounted a double vane rotor 19.

The cylindrical chamber 11 is divided into two sub-chambers 20 and 21 by a pair of sector abutments 22 and 23. These abutments are held in position by bolts 24 which pass through opposite walls 15 and 16, as well as through the center of the abutments to hold the same in fixed position. The circumferential length of these sectors

will naturally determine the length of the arcuate stroke of the motor.

The radial vanes 25 and 26 divide the sub-chambers 20 and 21 into two parts, the spaces 27 and 28 serving, when put under pressure, to cause counterclockwise rotation of the rotor, and the spaces 29 and 30 serving, when put under pressure, to cause clockwise rotation of the rotor.

When the diametrically opposed spaces 29 and 30, for instance, are put under pressure the spaces 27 and 28 are connected to exhaust whereby the rotor moves in one direction, and when the spaces 27 and 28 are put under pressure the spaces 29 and 30 are connected to exhaust to cause movement in an opposite direction. For maximum efficiency in operation, it is evident that the pressure spaces should be sealed from the exhaust spaces, or in other words, there should be as little leakage as possible of fluid from the pressure spaces into the exhaust spaces. To this end, the entire periphery of the blades are provided with spring pressed packing splines. As shown in Figure 1, the blade 25 is provided with two radial extending packing splines 31 and 32, which have a sliding fit in grooves 33 and 34 and a third packing spline 35 mounted in a groove 36 formed in the outer end of the vane and extending transversely thereof. A series of springs 37 serve to continuously urge these splines into engagement with the walls of the chambers. It will be noted that the vane 26 is provided with similarly arranged packing splines, and specific description thereof is not believed to be necessary.

In addition, the hub of the rotor 19 has circumferential finished surfaces 38 and 39 against which bear the spring pressed splines 40 and 41 which are mounted in the sectors 22 and 23 respectively. It will now be noted that the packing splines in the rotor serve to prevent leakage between chambers 27 and 29 and between chambers 28 and 30 and the packing splines 40 and 41 serve to prevent leakage between chambers 29 and 30 and between 27 and 28.

For the purpose of admitting and withdrawing fluid to and from these chambers, the wall 15 is provided with bores 42, 43, 44 and 45 which communicate with chambers 29, 27, 30 and 28 respectively. It will be noted that these bores terminate adjacent to opposite sides of the sectors and that the sectors themselves have grooves 46 cut in the side thereof adjacent these parts to insure the admission of fluid pressure at the beginning of the stroke and so that the vane 25

when at either end of its stroke will not close any of the ports.

For the purpose of automatically regulating the rate of flow to and from the control spaces of the motor a valve block 47 is attached to one end of the motor as by bolts 48. This valve block contains two throttle valve plungers 49 and 50 which are slidably mounted in slides 51 and 52. Each plunger has an axial hole 53, in one end of which is threaded a cam follower 54 and provided with a lock nut 55. A spring 56 is interposed in the bore between the end of the cam follower and a fixed pin 57, which has a sliding fit, with the other end of the bore. It will now be apparent that the spring tends to urge the plunger continuously in one direction and this is for the purpose of holding the cam follower 54 against a cam 58 which is keyed to the end of the drive shaft 17.

20 The two valve plungers are arranged diametrically opposite to one another and the cam 58 is provided with two control surfaces 59 and 60 which are exactly alike, as shown in the expanded view of the cam in Figure 2. The angular extent of the control surfaces 59 and 60, and indicated by the lines 61 and 62 respectively, is substantially equal to the angular extent of movement of the rotor. The curve 59 is of such a shape as to give constant acceleration as from 30 the point 62' to the point 63 and constant deceleration from the point 63 to the point 64. This form of curve is known as a gravity curve. If, now, the follower 54 of the throttle valve is at either point 62' or 64, and the cam is rotated in 35 such a direction as to cause the follower to traverse the curve, it will be apparent that, regardless of the direction of movement, that the throttle valve will move toward the right during the first half of the movement and toward the left during 40 the last half of the movement.

The valve housing has a pair of ports 65 and 66 to which are connected pipes 67 and 68 which may lead to a reversing valve or other suitable means for alternately supplying pressure to one 45 of these pipes and connecting the other to reservoir to obtain reversible operation of the motor. The port 65 is in constant communication with a groove 69 formed in the throttle valve plunger 49 by means of the annular groove 70 formed in the sleeve 56 and the radial ports 71 formed in the bottom of this groove. The sleeve 51 is provided with a second annular groove 72 in which is formed radial ports 73. These ports are adapted to be opened and closed by the tapered 50 portion 74 formed on the throttle valve plunger. In other words, when the plunger is all the way to the left, the port 73 is not entirely closed. This is for the reason that at the beginning of the next cycle, fluid must pass through this port 55 regardless of whether it is at the moment a pressure port or an exhaust port in order to start the parts moving again. The annular groove 72 is connected by a bore 74' to channel 43 which leads to chamber 21, and as shown in Figure 6, by the 60 channel 15 to the diagonally extending channel 16 which terminates as shown in Figure 5 in the channel 45 leading to chamber 28. Thus, the annular groove 72 is connected to diametrically opposite spaces 21 and 28 of the motor.

70 The sleeve 52 associated with the throttle valve plunger 50 has similar annular grooves 77 and 78, the former being in communication with the pipe 68 and the flow to the latter being controlled by the throttle valve plunger. The groove 78 is connected by a cross bore 79 to channel 44 leading to

motor space 30 and by drilled holes 79', shown in Figure 5, and vertical hole 80, shown in Figure 3, to channel 42 which communicates with motor space 29. By virtue of these connections, it will be apparent that the annular groove 78 in the 5 sleeve 52 is connected to the diametrically opposite motor spaces 29 and 30.

The manner of operation will now be briefly described. Assuming the two cam followers are bearing on the cam at the points 64 and 81 and 10 that pressure is being admitted to port 66, the fluid will flow to motor channels 42 and 44 by virtue of the fact that the throttle valve plunger 50 does not completely close channels 79 and 79', whereby the rotor will move in a clockwise 15 direction as viewed in Figure 4. As its movement progresses, the cam will be rotated by the drive shaft 12, and if in a downward direction as shown in Figure 2, the throttle valves will be gradually opened, thereby increasing the rate of flow and 20 causing constant acceleration in the movement of the rotor until the points 82 and 63 are reached on the cam, after which the rise on the cams will gradually close the throttle valves at such a rate as to cause a constant deceleration in the rate 25 of movement of the rotor. At the end of the stroke, the pressure in the actuating chambers will be so reduced as to prevent the vanes from striking the sectors a hard blow and thereby 30 causing damage to the parts.

It will be apparent that upon reversal of the connections to pipes 67 and 68 as by the reversing valve 82' that reverse rotation of the rotor may be effected.

For driving purposes, it will be apparent that 35 the shaft 12 may be provided on its free end with any suitable form of driver such as the enlarged head 83 having a cross slot 84 formed therein whereby suitable connection may be made with an Oldham coupling.

By providing two diametrically opposite vanes and simultaneously applying pressure to both of them in the same direction, that is, in a clockwise or counterclockwise direction, the parts are obviously balanced thereby, practically eliminating 45 friction and making it possible to develop a large torque on the driving shaft. By using the throttle valves on both the inlet and exhaust, the rate of movement of the motor is at all times under control, which is very important when moving 50 heavy parts because it prevents the momentum from becoming too great and makes it easier to stop the movement at the desired time and without shock.

What is claimed is:

1. A hydraulic motor having a housing, a plurality of chambers circumferentially arranged in said housing, a vane movable in each of said chambers, means connecting said vanes to a common rotor, a first channel for supplying fluid 60 under pressure to said chambers to apply an actuating force to the corresponding side of each of said vanes, a second channel means for conveying exhaust fluid from said chambers, a throttle valve in each of said channels, resiliently 65 operable means for normally urging said valves to an open position, and cam means carried by said rotor for positively moving said valves in a direction to throttle the flow in both of said channels.

2. A hydraulic motor comprising a cylindrical housing having a plurality of sector-shaped chambers circumferentially arranged therein, a vane movable in each of said chambers, a rotor integrally connected to each of said vanes, a pair 70

of pipes connected to said housing and adapted to be alternately connected to a pressure source and to exhaust, throttle valves respectively connecting said pipes to said chambers, and means responsive to rotation of said rotor for controlling the position of said throttle valves including a cam having a control surface in the form of a gravity curve.

3. A hydraulic motor comprising a housing having a cylindrical chamber formed therein, a rotatable shaft journaled in the end walls of said chamber, a pair of fixed abutments located between said end walls and dividing said chamber into two spaces, radial vanes attached to said shaft and projecting into said spaces, a valve block mounted on an end wall of said chamber, a pair of valve plungers slidably mounted in said valve block for movement in a direction parallel to the axis of said shaft, a passageway controlled by one of said valves and terminating in a pair of diametrically opposite ports, one in each space, whereby admission of pressure will cause said vanes to rotate in one direction, an additional passageway controlled by the other valve and terminating in a pair of diametrically opposite ports, one in each space, whereby admission of pressure will effect rotation of the vanes in an opposite direction, and cam means carried by the end of said shaft for effecting synchronized movement of said valve plungers.

4. A hydraulic motor comprising a housing having end walls and a cylindrical chamber formed therein, a shaft rotatably mounted in said end walls, means separating said chamber into two spaces, vanes projecting from said shaft into the respective spaces, each space having a pair of ports formed in one of said end walls, a valve housing supported by one of said end walls, a pair of pipes connected to said valve housing and adapted to be alternately connected to a source of fluid pressure and to exhaust, a pair of valve members mounted in said valve block for regulating the flow between the respective pipes and a respective pair of ports in said end wall, and means carried on the end of said shaft for simultaneously moving said valve members to increase and then decrease the rate of flow during one direction of rotation of said shaft.

5. A hydraulic motor comprising a housing having a cylindrical bore formed therein, end walls closing the end of said bore to form a cylindrical chamber therein, a shaft passing through said chamber and journaled in said end

walls, segments interposed between said walls and dividing said chamber into a plurality of spaces, said shaft having radial vanes projecting into the respective spaces and in sealing contact with the walls thereof, ports formed in one of said end walls and at opposite ends of said spaces and positioned in diametrically opposite pairs, a valve block attached to one of said end walls, means connecting one pair of diametrically opposite ports to a valve in said block, means connecting another pair of opposite ports to a second valve in said block, external channels connected to the respective valves, said channels adapted to be alternately connected to a source of pressure or to exhaust, said valves being normally in a slightly open position whereby upon admission of pressure to one of said channels, said vanes will be actuated to cause rotation of the shaft, and means responsive to rotation of the shaft to effect further and simultaneous opening of said valves to increase said rate of rotation to a predetermined maximum.

6. A hydraulic motor comprising a housing having a cylindrical bore formed therein, end walls attached to said housing to form a cylindrical chamber therein, a shaft passing through said chamber and journaled in the opposing end walls, segments interposed between said walls and dividing said chamber into two spaces, said shaft having radial vanes projecting into the respective spaces and in sealing contact with the walls thereof, ports formed in one of said end walls and at opposite ends of said spaces and positioned in diametrically opposite pairs, a valve housing attached to one of said end walls, means connecting one pair of diametrically opposite ports to one of said valves, means connecting the other pair of opposite ports to the other valve, a pair of external channels connected to the respective valves, said channels adapted to be alternately connected to a source of pressure and to exhaust, said valves being normally in a slightly open position whereby upon admission of pressure to one of said channels said vanes will be actuated to cause rotation of the shaft, means responsive to rotation of the shaft to effect further and simultaneous opening of said valves to increase said rate of rotation, said last named means also acting to close said valves during the last half of the stroke of said vanes to effect deceleration of said shaft.

HERMAN HORLACHER.
